UNITED STATES PATENT OFFICE.

ALEXANDER BRADY, OF NEWTON LOWER FALLS, MASSACHUSETTS, ASSIGNOR TO NEW ENGLAND CONFECTIONERY COMPANY, OF BOSTON, MASSACHUSETTS, A CORPORATION OF MASSACHUSETTS.

MACHINE FOR DUMPING MATERIAL.

1,253,343.

Specification of Letters Patent. Patented Jan. 15, 1918.

Application filed January 2, 1913. Serial No. 739,693.

To all whom it may concern:

Be it known that I, ALEXANDER BRADY, of Newton Lower Falls, in the county of Middlesex and State of Massachusetts, have invented certain new and useful Improvements in Machines for Dumping Material, of which the following is a specification.

This invention relates to a machine for dumping material and more particularly to 10 a machine for dumping small articles, such as wafers or the like.

In the manufacture of candy wafers it has been the common practice to dump the trays or boards containing the wafers by hand, one 15 tray at a time, so that the wafers slide off into a box or bucket. In this operation a considerable percentage of the wafers is broken, thus entailing a severe loss, and the 20 operation of picking up a tray from one pile of them, dumping it, and then placing it in another pile, consumes a considerable amount of time and consequently is expensive.

The primary object of this invention is to 25 provide a means to overcome the difficulties above set forth by providing a device whereby a pile of trays or boards may be dumped at a single operation and with an extremely small percentage of breakage of the wafers.

30 In the accompanying drawings Figure 1 is a side elevation of an illustrative embodiment of the invention in upright position, Fig. 2 is a longitudinal vertical section of the same, Fig. 3 is a similar view with the 35 device in dumping position, Fig. 4 is a horizontal section, Fig. 5 is a fragmentary sectional elevation, and Fig. 6 is a fragmentary sectional elevation of a truck with a pile of trays thereon.

40 As illustrated in the drawings the device comprises a holder or jacket composed of a top 10, bottom 12, and sides 14, 16, said holder being provided at its rear with a chamber or extension forming a trough 18 having a rear wall 20, side walls 22, 24, and a bottom wall 25 raised slightly above the level of the bottom 12. The side walls 22, 24 of the trough extend between the side walls 14, 16 of the holder, and their inner 45 vertical edges 26 act as stops for the trays, as will be hereinafter explained.

The trough 18 is divided by the shutters

or partitions 28 into compartments 30. The shutters 28 and the end wall 20 are relatively movable; preferably the shutters are pivotally connected at their inner edges to the side walls 22, 24, and have their outer edges engaged by stops 32 when the device is in upright position, as shown in Fig. 2.

The holder is adapted to receive a truck 34 which carries a pile or stack of trays 36. Each tray comprises a bottom 38 and shallow sides 40, the front and rear edges or walls of the tray being omitted, thus providing a wide, shallow trough-shaped tray. 65 These trays are adapted to carry thin candy wafers, or whatever other material is desired to be dumped, and are piled one on top of the other upon the truck, so that when the truck is loaded it will just pass between the 70 side walls 14, 16. The rear or entering faces of said trays being adapted to engage the stops 26 to limit the movement of the load into the holder.

The shutters 28 are located at intervals 75 of four or five trays and their upper surfaces are substantially a continuation of the upper surfaces of the bottoms of the corresponding trays, so that when the wafers are discharged from the trays they will fall only 80 a short distance before striking a shutter, thus preventing breakage.

The holder for the truck and trays is pivotally supported by a shaft 42, suitably journaled in uprights 44, 46 of a supporting 85 framework. The shaft 42 is provided with a crank 48, and a pair of winding drums 50, 52, upon which one end of cables 54 and 56, respectively, is wound. The other ends of said cables are attached to eye bolts 60 located near the forward edge of the sides of the holder and below the center, said cables passing over pulleys 61 mounted on the uprights 44 and 46. The bottom 12 of the truck holder is let into a shallow pit 62 in the 95 building floor 64 so that the upper surfaces of said bottom and floor are flush, to facilitate the movements of the truck with its load into and out of the holder. A catch 66 is provided on the under side of the trough 18 to engage a stop 68, whereby the holder is held in upright position, said catch being adapted to be released by a foot-lever 70, fulcrumed at 72 and adapted to engage the

under side of said catch when its right-hand end, as seen in Fig. 5, is pushed down by the foot of the operator.

A counterweight 74 is connected to one end of a cable 76 passing over a pulley 78 and attached at its other end to an eye-bolt 80 on the top 10 of the holder. This weight tends normally to tilt the holder with its loaded truck into the position shown in Fig. 3, but is restrained by the catch 66. When this catch is released and the crank 48 turned to wind up the tables 54 and 56, the holder swings up out of the pit 62 under the combined action of the cables 54, 56 and 76, and swings over into the position shown in Fig. 3. During the first portion of the movement the weight 74 assists in pulling the holder and load over, but when the center of gravity of this pivoted load passes to the left of the vertical line through the shaft 42, the weight 74 opposes that of the holder and its load and thus prevents a too sudden descent of the top end of the holder, the cables 54 and 56 being then paid out by reversing the direction of rotation of the crank 48.

The top of the trough 18 is normally closed by a door or closure 81, hinged at 82, and having an eye-bolt 84 at its other edge connected to one end of a cable 86 passing over a pulley 88 mounted in a bracket 90 on the top 10 of the holder. The other end of said cable is connected to a counterweight 92 which is slidable in a chute 94 on the top 10. When the device is in its upright position the door 81 is closed, but as the device is tilted toward the left the weight 92 slides downward to the left in the chute 94, thus opening said door. When the device is tilted sufficiently for the wafers to slide off the trays they fall onto the upper sides of the shutters 28 and against the rear wall 20 of the trough 18. The continued rotation of the device brings the wall 20 to form the bottom of the trough 18, and the shutters 28 swing into vertical position away from the stops 32, thus enabling the wafers, or other material, to slide along the wall 20 and out through the open end of the trough 50 into any suitable receptacle. All of the trays are emptied simultaneously and the mass of wafers falls such a short distance that there is practically no breakage.

When it is desired to return the device to normal position the crank is turned toward the right to wind up the cables 54 and 56, which are now in crossed position. When the center of gravity of the device passes to the right of the vertical line through the shaft 42, the cables are paid out and its weight is sufficient to overcome the counterweight 74, and it returns to normal position.

While I have described the invention as particularly adapted for use with candy

wafers, it is to be understood that its use is in no wise limited thereto.

What I claim is:—

1. A device of the character described, comprising means for supporting a pile of trays and holding them against lateral displacement when inverted, said means being arranged to be tilted, and means movable with said supporting means for receiving the contents of the trays when the latter are moved into discharging position.

2. A device of the character described, comprising a holder arranged to be tilted and having means for confining a truck load of trays, a trough arranged to receive the material discharged from said trays, means for dividing said trough into vertically disposed compartments when said holder is in upright position, said dividing means being arranged to automatically afford a free passage through said trough when the latter has been tilted into discharging position.

3. A device of the character described, comprising a pivotally mounted holder adapted to confine a pile of trays when inverted, and means for receiving the material discharged from said trays when they are swung into discharging position, said means being provided with partitions arranged at intervals opposite the ends of the trays.

4. A device of the character described, comprising a holder adapted to contain a pile of trays, means for tilting said holder, and counterweighting means adapted to assist the tilting movement of said holder during a portion of its travel and to retard the movement of the holder during the remainder of its movement.

5. A device of the character described, comprising a holder adapted to contain a pile of trays, means for tilting said holder, counterweighting means adapted to assist the tilting movement of said holder during a portion of its travel and to retard the movement of the holder during the remainder of its movement, and a compartment for receiving the material discharged from said trays.

6. A device of the character described, comprising a holder adapted to contain a pile of trays, means for tilting said holder, counterweighting means adapted to assist the movement of said holder during a portion of its travel and to retard the movement of said holder during the remainder of its movement, a compartment for receiving the material discharged from said trays, and a closure for said compartment arranged to be automatically opened and closed.

7. A device of the character described, comprising means for supporting a pile of trays and holding them against lateral displacement, said means being arranged to be tilted, means for holding the device in up-

right position, means for imparting an initial rotary movement to the device, and means assisting said rotary movement and automatically checking the rotation of the 5 device.

8. A device of the character described, comprising means adapted to confine a pile of trays and to tilt them to discharge their contents, means arranged to initially assist 10 the tilting movement, said means being also arranged for automatically checking said tilting movement.

9. A device of the character described, comprising a holder adapted to confine a 15 pile of trays, and a plurality of shutters arranged at intervals to form continuations of the bottoms of the trays.

10. A device of the character described, comprising a holder adapted to confine a 20 pile of trays, means for inverting said holder, and a plurality of compartments arranged opposite the trays adapted to receive the contents of the trays when said holder is inverted.

11. A device of the character described, comprising a pivotally mounted holder 25 adapted to confine a pile of trays, a series of compartments communicating with said holder closed against discharge while the holder is in upright position, but arranged to automatically afford a free passage for the contents of said trays when the holder is swung into discharging position, means for tilting said holder, and means for retarding 30 the tilting movement of said holder.

12. A device of the character described, comprising a holder, a chamber communicating with said holder, and a plurality of shutters for dividing the chamber into 40 compartments, said shutters and a wall of said chamber being arranged for relative movement to provide a passage at the ends of said shutters when the holder is moved into discharging position.

13. A device of the character described, comprising means for supporting a pile of 45 trays, means for tipping the trays to discharge their contents, means located at intervals along the pile of trays upon which the contents of the trays first fall during their discharging movement, and means for receiving the contents when they pass from said last mentioned means.

14. A device of the character described, 55 comprising pivotally mounted means adapted to confine a pile of trays, means for tilting the device, and counterweighting means arranged to assist the tilting movement of the device at the commencement thereof and to retard said movement when the trays are moved into discharging position.

15. A device of the character described, comprising a holder mounted to swing about a horizontal axis and having an open front, 60 to receive a stack of trays, a back for said

holder, and a series of partitions arranged at intervals opposite the ends of the trays to form compartments.

16. A device of the character described, comprising a stack receiving jacket mounted 70 to swing about a transverse axis and having a series of transverse partitions arranged to form compartments into which the trays can be discharged, said compartments having provision whereby they may be emptied of 75 their contents after having received the material from the trays.

17. A dumping machine of the nature described, comprising a chamber mounted to swing and having a back forming a chute 80 and a discharge opening adjacent one end of said chute, and a series of movable gates for said chute.

18. A dumping machine of the nature described, comprising a chamber mounted to 85 swing and adapted to receive a series of trays in stack form, said chamber having at one end a discharge opening, and a series of gates pivotally mounted in said chamber and forming a series of receptacles into which 90 said trays may discharge.

19. An apparatus of the class described comprising, in combination, a carrier for receiving a conveyance and movable to tilt the 95 conveyance to discharge the contents thereof; and shutter means movable with said carrier for controlling the discharge.

20. An apparatus of the class described comprising, in combination, a carrier having provision for receiving an assembly of trays; 100 means to actuate said carrier to discharge the contents of said trays; and guides on said carrier coöperating with said trays for contributing to the discharge of the contents from the latter.

21. An apparatus of the class described comprising, in combination, means for holding a pile of trays in assembled relation; receiving means movable with said trays for receiving the contents thereof; means to 110 manipulate said receiving means and said pile of trays as a unit to slide the contents of said trays into said receiving means; and means coöperating with said receiving means to control the delivery therefrom.

22. An apparatus of the class described comprising, in combination, means for receiving and holding a pile of trays in assembled relation, said means having provision permitting the same to be tilted to 120 simultaneously slide the contents of said trays therefrom; and means movable with said trays for receiving and checking the fall of said contents, and having provision permitting the delivery of said contents to a 125 receptacle.

23. A machine for dumping articles comprising in combination a carrier for an assembly of trays for receiving the articles, means to manipulate said carrier to slide the 130

- articles along said trays, a discharge gate, and means including a weight for automatically shifting said gate in the course of the manipulation of said carrier.
- 5 24. A machine for dumping articles comprising in combination a carrier for an assembly of trays for receiving the articles, means to manipulate said carrier to slide the articles along said trays, a discharge gate 10 for the carrier, and means for automatically

operating the same including a pocket on said carrier and a weight adapted to slide in said pocket.

In testimony whereof I have affixed my signature, in presence of two witnesses.

ALEXANDER BRADY.
